CLAIM

The ornamental design for a baseball equipment cart, as shown and described.

DESCRIPTION

FIG. 1 is an upper left perspective view which is identical to an upper right perspective view of the baseball equipment cart showing my new design;

FIG. 2 is a bottom plan view thereof;

FIG. 3 is a rear elevational view thereof; and

FIG. 4 is a top plan view of a baseball equipment cart showing a second embodiment of my new design, it being understood the sole difference resides in the cart having an additional conveyance tube member.
